UNITED STATES PATENT OFFICE.

WILLIAM C. EHMKA, OF DETROIT, MICHIGAN, ASSIGNOR TO DETROIT SHEET METAL WORKS, OF DETROIT, MICHIGAN, A PARTNERSHIP FIRM.

INDUSTRIAL OVEN.

Application filed June 14, 1920. Serial No. 388,974.

To all whom it may concern:

Be it known that I, WILLIAM C. EHMKA, a citizen of the United States, residing at the city of Detroit, county of Wayne, State of Michigan (whose post-office address is 453 Kitchener Ave.), have invented certain new and useful Improvements in an Industrial Oven, and declare the following to be a full, clear, and exact description of the same, such as will enable others skilled in the art to which it pertains to make and use the same, reference being had to the accompanying drawings, which form a part of these specifications.

15 The objects of my invention are to secure an industrial oven of portable construction, and provide means for the heat expansion of the walls which will prevent buckling of the wall plates.

20 Another object is to provide a heat insulated joint whereby no single piece of metal extends through the wall, and thereby reduce the loss of heat due to conduction of the metal, and its surface radiation.

25 It is still a further object of the invention to secure simplicity in construction and efficiency and ease in operation of the oven.

These several objects are secured in their 30 preferred form by the construction and arrangements of parts as are more fully herein-after described.

Similar parts on all drawings are marked by similar numerals.

35 Fig. 1 is a top view of the oven, showing in plan the ventilating system, and the general construction of the oven unit.

Fig. 2 is a front view of the oven showing the entrance door and air circulating 40 system.

Fig. 3 is a side view of the oven, also showing the circulating system and the air chambers.

Fig. 4 is a rear view of the oven and 45 circulating system.

Fig. 5 is a sectional view —AA— as is shown on Fig. 1, showing the general construction of the oven walls and the interior circulation.

50 Fig. 6 is a sectional view —BB— as is shown on Fig. 1, showing the special roof construction and the baffle plates in the circulating system.

Fig. 7 is a sectional view —CC— as is

shown on Fig. 2, showing the panel construction of the walls.

Fig. 8 shows the panel joint in the wall construction for the insulation and heat expansion.

Fig. 9 shows the panel joint of the roof construction and provisions for the heat expansion.

Fig. 10 shows the door construction with insulation.

I will now describe more fully the detail 65 construction and the working parts thereof, referring to the accompanying drawings and the marks thereon.

The general construction of the oven walls consists of portable rectangular panels which 70 are fastened together in erecting the oven.

The floor is constructed of a suitable heat insulating material and placed on the oven foundation. Mounted on the floor slab are the wall panels 2, comprised of a sheet metal 75 jacket riveted together to form a hollow rectangular panel, and filled with a heat retaining material. These slabs are securely fastened together at the edges by means of lap joints and screws as shown in Fig. 8. 80 The joint also provides a space between the edges of the panels which is to be filled with loose heat retaining material thus giving the panel room to expand. The panels are held in place by means of angle irons 3 and 4, securely fastened to the edge of the floor slab by anchors 50 and allowing the wall panels to slide freely therein. The wall corners 85 7 and 8 are separate units but of similar construction to the wall panels, and are joined to the wall panels as is shown in Fig. 8.

Along the top edge of each of the side walls is fastened an angle iron 5 by means of anchors 51. Between the T-bar supports are placed the roof slabs 9, which are of similar 90 construction to the wall panels, but herein-after more fully described, and comprised of sheet metal riveted together to form a hollow rectangular panel which is filled with a heat insulating material. An opening is 95 left between the edges of roof panels which is filled with the loose heat insulating material, and is held in place by the cover plate 16, by means of screws, and slotted holes to allow for expansion. The roof panels extend slightly beyond the inner edge of the wall panels to form a seal for retaining the loose insulating material in the corner, and 100 105

is covered by the cornice 10. The cornice is secured to the side walls and the roof.

At the front side of the oven are the swinging doors 11 mounted by the hinges 12, and 5 securely fastened to the corner units 8, thus giving free access to the oven for placing or removing materials for drying.

The panel construction is shown in detail in Fig. 7 and Fig. 8. It is the intention of 10 the inventor to make these panels of a uniform construction so that a standard panel may be used for the entire wall. The panels are to be placed in alternate position as is shown in Fig. 7, thus giving uniformity to 15 the wall, yet maintaining a solid and rigid unit construction. The size of the oven may be varied by changing the number of wall panels in the construction thereof. Fig. 8 shows in detail the wall panel joint. The 20 side walls 13 are sheet metal of suitable gage and are connected by an edge plate 14 bent in a zig-zag to receive the sheet of asbestos 15, or any other heat insulating material, which is placed between the side walls and 25 the edge plate so there is no steel to steel contact, and the heat loss by conduction is brought to a minimum, as no steel part extends through the wall. The wall slabs or panels when placed together provide a complete insulated joint of non-conducting heat 30 material, and are joined together by means of lap-joints and screws, and forming a hollow joint which is filled with a loose heat insulating material to allow for the expansion 35 of the panels due to the oven heat.

The detail of the roof joint is shown in 40 Fig. 9. The side walls 17 are sheet metal of suitable gage, and are connected by the edge plate 18 bent in a zig-zag shape to receive the sheet of asbestos insulating 19. The insulating is so placed as to prevent any steel to steel contact, thus reducing the loss of heat through the conduction of the metal. No 45 piece of metal passes through the panel. The edges of the panels rest on the T-bar supports and are held in place by the cover plates 16 which are fastened to the edges. The joint between the edge of the roof panels is filled with a loose heat insulating material to allow the free movement thereof 50 when expanding, and to give the roof the effect of a solid and continuous insulated slab.

The wall can be made of any desired thickness for retaining heat to any degree. Likewise the panels may be made of any desired 55 width.

The door construction is to be similar to that shown in Fig. 10, making as nearly an air tight joint as possible. The side wall 60 plates are also connected with a zig-zag plate 20, and insulated therefrom by the asbestos sheet 21 placed to prevent any steel to steel connection, thus reducing the loss of heat due to conduction and radiation to 65 a minimum.

The oven may be used as a single unit, or in a series of ovens placed side by side and using a common wall between.

Inside the oven, and supported by the walls, are the heat units 42, so placed as to come in contact with all the air from the circulating fan as it enters the oven through the portals 34 and by means of the baffle plate 35. The heat unit may be of any desired type. 75

In connection with the oven is a ventilating system comprised of the double fans 22 and 23. These fans may be located at the top of the oven or at any convenient location. 80

The double fans are placed on a common shaft and supported by the main pedestal 25, and operated by the drive belt 24. Fan 23 is the circulating fan drawing its supply of air for the oven from the exhaust chamber 26 and the breather 27. The exhaust chamber 26 is located in the roof of the oven and receives the light heated air therein and is mixed with the fresh air from the breather 27 in such proportions as may be desired, by means of the damper 28. The supply coming through the exhaust chamber 26 may also be regulated by means of the damper 29 placed in the circulating pipe 30. The supply fan 23 exhausts the air into the 90 circulating pipes 31 and 32, and into the lower plenum chambers 33, and thence distributed through the portals 34 into the oven. Inside the oven and opposite the 95 portals 34 are baffle plates 35 which start 100 the air in an upward direction and passing through the heating units diffuses through the entire oven. The heavy gases and fumes from the baking material settle to the bottom of the oven and are drawn off through 105 the portals 36 into the exhaust chamber 37. Chamber 37 is exhausted by means of the exhaust fan 22, drawing the air through the pipes 38 and 39, and exhausting same through the outlet 40 into a chimney. The 110 amount of air drawn from the exhaust chamber 37 may be regulated by means of the dampers 41 placed in the exhaust pipes 38 and 39.

In describing the above invention, I desire 115 it to be understood that the same is merely illustrative of the oven now in use, and I do not wish to be confined to the precise construction and arrangement of parts as shown. The above description is to include 120 any substitute construction and arrangements of parts which are obviously equivalent to those herein described.

Having fully described the oven, what I claim as my invention and desire to secure 125 by Letters Patent is:

1. A portable oven, with walls comprising a combination of detachable heat insulated panels, means for supporting same, means for connecting same by a heat insulated 130

joint, heat insulated ceiling slab and means for connecting same by heat insulated joints.

2. In an oven, with both walls and ceiling comprising a combination of detachable heat insulated panels, means for supporting same, means for joining said panels together by heat insulated joints, means for joining the ceiling and wall panels, a heat insulated floor, and means for connecting the wall panels thereto and means for wall expansion thereon.

3. An oven, with walls, ceiling and floor comprising a combination of detachable heat insulated panels, means for supporting same and means for joining said panels together with heat insulated joints.

4. In an oven, with walls and ceiling com-

prising detachable heat insulated panels, means for supporting said panels, means for connecting said panels together, and means for insulating the panel joints.

5. In a detachable wall panel joint, in combination with an oven, a heat insulated edge plate connecting the side walls, means for insulating said edge plate from the side walls, means for joining the panels together, means for insulating the joint between panels.

In testimony whereof, I, WILLIAM C. EHMKA, sign these specifications.

WILLIAM C. EHMKA.
